NUMBER BOARD FOR A MATHEMATICS TEACHING DEVICE

Rudolph Ringhofer, Flossmoor, Ill., assignor to La Pine
Scientific Company, Chicago, Ill., a corporation of
Illinois

Filed July 6, 1965, Ser. No. 86,030

Term of patent 14 years

(Cl. D25—1)

FIGURE 1 is a top plan view of a number board for a mathematics teaching device embodying the new design;

FIGURE 2 is a front elevational view thereof;

FIGURE 3 is a rear elevational view thereof;

FIGURE 4 is a cross sectional view taken along the lines 4—4 of FIGURE 3;

FIGURE 5 is an end elevational view thereof; and

FIGURE 6 is a perspective view of a portion of one end of the number board.

The dominant features of my design reside in the portions shown in full lines.

I claim:

The ornamental design for a number board for a mathematics teaching device, as shown and described.
